MOTOR HOME GRILL

Marvin E. Nerem, Minneapolis, Minn., assignor to Winnebago Industries, Inc., Forest City, Iowa, a corporation of Iowa

Filed Nov. 8, 1968, Ser. No. 14,356

Term of patent 14 years

Int. Cl. D12—14
U.S. Cl. D14—18

FIG 1

The broken line portions of the motor home are shown for illustrative purposes only.

I claim:

The ornamental design for a motor home grill, substantially as shown and described.
